Primary Examiner — Ruth McInroy(74) *Attorney, Agent, or Firm* — Cantor Colburn LLP(57) **CLAIM**

The ornamental design for an intake for cleaner, as shown and described.

DESCRIPTION

FIG. 1 is a top perspective view of an intake for cleaner, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a bottom perspective view thereof; and,

FIG. 9 is another side view thereof as shown in another configuration.

The broken lines are for environmental purpose only and form no part of the claimed design.
